UNITED STATES PATENT OFFICE.

RAYMOND CALPIN, OF EVERETT, MASSACHUSETTS, ASSIGNOR TO A. S. CAMPBELL COMPANY, OF EAST BOSTON, MASSACHUSETTS, A CORPORATION OF MASSACHUSETTS.

CURTAIN-WINDOW INSTALLATION.

Application filed January 14, 1925. Serial No. 2,286.

This invention aims to provide an improved curtain window installation.

In the drawings, which illustrate three preferred embodiments of my invention:

5 Figure 1 is an elevation view of the installation, partly broken away to show the elements for securing the frame parts to the curtain;

10 Fig. 2 is an edge view of the installation without the glass and showing the normal flex of the frame;

Fig. 3 is a view similar to Fig. 2, showing the installation after the glass has been inserted;

15 Fig. 4 is an enlarged section on the line 4—4 of Fig. 1;

Fig. 5 is an enlarged section on the line 5—5 of Fig. 1;

20 Fig. 6 is a fragmentary view of one end of the installation showing the end of one of the frames removed to permit changing the glass;

25 Fig. 7 is a fragmentary view of a portion of the installation showing a second form of tension device;

Fig. 8 is a section on the line 8—8 of Fig. 7;

30 Fig. 9 is an end elevation of the installation with the end of one of the frames removed to show how the glass is placed in the frame; and

Fig. 10 is a section similar to Fig. 5, but showing the curtain arranged differently in relation to the glass.

35 Referring to the drawings, I have shown a curtain window installation which includes a frame having a removable end portion. The frame members of the frame, except the removable end, are permanently secured to the curtain fabric and the glass may be removed and replaced simply by removing the removable end portion of one of the frame members, thereby to permit sliding the glass in and out of the fixed part 40 of the frame, in a plane parallel with the frame parts.

45 Thus I have provided a curtain window installation which is neat, simple, inexpensive and durable, and is very desirable because the glass may be changed any number of times without affecting the means by which the frame members are secured to the curtain.

50 Referring now to the installation shown

in Figs. 1 through 6, I have shown a frame 55 of which the greater part is permanently secured to the curtain fabric 1. This frame comprises a prong-presenting frame part 2 and a prong-receiving and glass-holding frame part 5 secured to opposite sides of the curtain 1 by a plurality of prongs 3, which pass through the curtain and through slots 4 in the frame part 5. After the prongs are clenched against the frame member 5, the upstanding flange 6, shown in dotted lines 65 in Fig. 4, is bent inwardly and downwardly against the prongs 3 to conceal them.

60 The inner portion of the glass-holding frame part 5 presents an angle shaped portion 6^a which provides a continuous groove 70 for reception of the glass 7, as best shown in Figs. 4, 5 and 9.

65 The glass-holding frame member is preferably provided with a removable end portion 8 (Figs. 1 and 6), so that the glass may 75 be slid into and out of the glass-holding frame without removing the rest of the frame parts from the curtain. While the frame parts may be perfectly flat, I have found that the glass can be held more firmly 80 in the frame by initially flexing both frame members, as shown in Fig. 2. Thus when the glass is slid into the groove provided by the glass-holding frame, the frame is flattened, as shown in Fig. 3, and a tension 85 is exerted upon the glass to prevent it from rattling in the frame.

70 The removable end portion 8 may be secured in position to keep the glass from sliding out of the frame part 5 by a plurality of attaching screws 9, preferably of the self-piercing type. These screws may be located at the corners of the frame where the flange 6 is cut out to turn the corners 95 of the frame part 5, and they extend through the cloth and thread themselves into indentations in the prong-presenting frame part 2, as shown in Fig. 5.

75 The frame part 2 is provided with an outwardly extending central beaded portion 10, 100 which stiffens the frame part and also provides a recess into which the self-piercing screws 9 may extend (Fig. 5) after threading themselves into the frame part 2.

80 When the frame parts 2 and 5 are assembled to the curtain and the glass is inserted into place, the curtain 1, which is gripped between the frame members, extends 105

inwardly so as to provide a cushion between one side of the glass and the frame part 2. Thus any undue pressure exerted upon the glass by the natural tendency of the frame to flex, will be offset by the cushioning effect of the curtain 1.

Referring now to Figs. 7 and 8, I have shown means for holding the glass securely within the frame to prevent rattle, when 10 the frame parts are made flat. The frame parts, in this instance, are exactly as shown and described in relation to the first preferred embodiment of my invention, except that in place of making them initially flexed, 15 I have provided a plurality of pockets 12 in the upper part of the angle-shaped portion 6^a for receiving suitable flexible material to press upon the glass 7. The pockets 12 are spaced about the frame part 5 and are 20 preferably curved in cross-section so as to provide a narrow opening between the glass 7 and the inner edges of the frame part 5, as shown in Fig. 8.

The flexible material preferably comprises short round rubber strips 13 which, 25 when forced into the pockets 12, are compressed and exert pressure upon the glass, thereby forming a cushion between the glass 7 and frame 5.

Referring now to Fig. 10, which illustrates a third form of providing a tension on the glass to prevent rattle and breakage thereof, I have provided frame members, substantially the same as shown in Figs. 1 30 to 6 inclusive. In this instance, the glass lies next to the frame part 2 and the curtain 1 is interposed between the glass and the upper portion of the angled portion 6^a of the frame part 5, as best illustrated in Fig. 40 10. The curtain 1 is adhesively secured to the angled portion 6^a so that the glass 7 may be slid in and out of the frame without wrinkling the curtain.

While I have shown and described preferred embodiments of my invention, it will 45 be understood that changes involving omission, substitution, alteration and reversal of parts, and even changes in the mode of operation, may be made without departing from the scope of my invention, which is best defined in the following claims.

Claims:

1. A curtain window installation comprising, in combination, a glass, a curtain, a sheet metal glass-supporting frame having a portion thereof permanently secured to the curtain and having a portion removably secured to the permanently secured portion of the frame, whereby said glass may be quickly removed and replaced by simply removing the removable portion.

2. A curtain window installation comprising, in combination, a glass, a curtain, a frame part secured permanently to one side 55 of the curtain, a second frame part secured

to the opposite side of the curtain, the glass being held in position by said frame parts and a removable frame portion permitting quick change of the glass without disturbing the remainder of the installation.

3. A curtain window installation comprising, in combination, a glass-retaining frame, part of which is permanently secured to a curtain and the other part detachable from the permanently secured portion, a flange 70 provided by said glass-retaining frame to form a continuous groove between said flange and said curtain, a removable glass adapted to fit into said groove, and tension means provided by said frame member to 75 secure said glass securely within said groove.

4. A curtain window installation comprising, in combination, a glass-retaining frame, means for permanently securing a portion 80 of said glass-retaining frame to a curtain, an end portion of said glass-retaining frame removable from the rest of the frame and a glass adapted to slide into the open end of 85 said glass-retaining frame when said end portion is removed.

5. A curtain window installation comprising, in combination, a glass-retaining frame member, a second frame member having integral means for permanently securing both frame members to opposite sides of a curtain, a removable end portion presented by 90 said glass-retaining frame member and a glass adapted to slide into the open end of said glass-retaining frame member when said end portion is removed.

6. A curtain window installation comprising, in combination, a glass-retaining frame member, a glass and a second frame member, means securing said frame members to opposite sides of a curtain, said curtain interposed between one of said frame members and a portion of the glass adjacent the edge of said glass to cushion said glass, and one of said frame members having a removable portion to permit renewal or withdrawal of 100 said glass while permitting the rest of said frame member and the other frame member to remain fixed to the curtain.

7. A curtain window installation comprising, in combination, a glass-holding frame 115 presenting a glass-receiving groove, a curtain slidably engaged in said groove, a curtain interposed between said glass and one side of said groove to cushion the glass means securing a portion of said frame in fixed relation 120 to the curtain and a removable portion of said frame for permitting sliding of said glass into and out of said groove while the remainder of said frame remains secured to the curtain.

8. A curtain window installation comprising, in combination, a curtain, a frame part located at one side of said curtain, a second frame part located at the opposite side of the curtain, means permanently securing all 130

of said first-mentioned frame part and a portion of said second-mentioned frame part to said curtain, a glass held between said frame parts and a quick detachable end portion of said second mentioned end part which, when removed, permits insertion and removal of the glass by sliding movement

and means for securing said quick detachable end portion to said first-mentioned frame part.

In testimony whereof, I have signed my name to this specification.

RAYMOND CALPIN.
